DIE PRESS PLATEN

Robert Garwin, % Ormont Machine Co. Inc., 687 Broadway, New York, N.Y. 10012

Continuation-in-part of design application Ser. No. 10,442, Feb. 5, 1968. This application Nov. 4, 1968, Ser. No. 14,674

Term of patent 14 years

Int. Cl. D15—05

U.S. Cl. D63—1

FIG. 1

FIG. 2

FIG. 3

FIG. 4

FIG. 5

FIG. 1 is a front view of my new design for a die press platen as mounted in a die press, said die press being shown in phantom lines for illustrative purposes only;

FIG. 2 is a front view of the die press platen;

FIG. 3 is a side view thereof;

FIG. 4 is a top view thereof the bottom view being substantially identical thereto; and

FIG. 5 is a horizontal section through the die press platen.

This design patent application is a continuation-in-part of my application Ser. No. 10,442 filed Feb. 5, 1968, entitled; Die Press Platen, and now abandoned.

I claim:

The ornamental design for a die press platen, as shown and described.
